(57) **CLAIM**

The ornamental design for a pool pump, as shown and described.

DESCRIPTION

FIG. 1 is a front, left and top perspective view of a pool pump showing my new design;
 FIG. 2 is a rear, right and bottom perspective view thereof;
 FIG. 3 is a front view thereof;
 FIG. 4 is a rear view thereof;
 FIG. 5 is a left side view thereof;
 FIG. 6 is a right side view thereof;
 FIG. 7 is a top plan view thereof;
 FIG. 8 is a bottom plan view thereof;
 FIG. 9 is an enlarged view of area 9 in FIG. 1; and,
 FIG. 10 is an enlarged view of area 10 in FIG. 2.
 The broken lines in the figures illustrate portions of the pool pump that form no part of the claimed design. The dot-dash broken lines represent boundaries of the enlarged portions and form no part of the claimed design.

1 Claim, 10 Drawing Sheets(56)
